J. K. HOFFMAN

MUTE

Filed Sept. 2, 1921

UNITED STATES PATENT OFFICE.

JOSEPH KEMP HOFFMAN, OF BALTIMORE, MARYLAND.

MUTE.

Application filed September 2, 1921. Serial No. 497,905.

To all whom it may concern:

Be it known that I, JOSEPH K. HOFFMAN, a citizen of the United States, residing at Baltimore, in the county of Baltimore and 5 State of Maryland, have invented certain new and useful Improvements in Mutes, of which the following is a specification.

This invention relates to a mute for use in muffling the tones of wind instruments 10 such as cornets, bugles, trombones and the like.

Most of the mutes in use with which I am familiar at the present time are constructed of metal, papier-mâché, guttapercha or similar substances, all of which are of such a 15 nature that they either alter or tend to alter the pitch of the instrument with which they are used. And furthermore, mutes constructed of metal impart a strident quality 20 to the tone of the instrument which is very objectionable; mutes of papier-mâché absorb moisture which causes the mute to break down after a short time, and mutes of gutta-percha do not have the ability to impart a 25 well modulated tone to the notes issuing from the instrument. Therefore, one of the objects of the present invention is to provide a mute embodying the highly resonant features of thin wood, together with the lasting 30 qualities thereof.

Another feature resides in providing a veneered structure built upon a hard pan or press board base, thus rendering the structure impervious to moisture.

Still another object is to provide a mute which is constructed by wrapping a base material about a mandrel of conical form until the edges meet in a butt joint, then placing an overlying strip along the butt 40 joint, and finally wrapping the conical base with a wood veneer and then closing one end of the mute thus formed with a substantially non-vibrating diaphragm.

With the above, and other objects in view, 45 I will now describe a specific form of the invention which I have shown in the accompanying drawings by way of illustration, and wherein:

Figure 1 is a perspective view showing 50 the manner of forming the base of the mute.

Fig. 2 is a similar view showing the base formed on the mandrel and with the wood veneer ready to be applied thereto.

Fig. 3 is a longitudinal section of a completed mute. 55

Fig. 4 is a transverse section of the completed mute, and

Fig. 5 is a perspective view of the completed mute.

In detail:

The mute, as herein shown is formed on a tapered or conical shaped mandrel 1 having the spindle 2' for mounting in a lathe or the like.

In forming the base of the mandrel a 65 piece of press board or other suitable substance is cut to substantially triangular form with the apex removed and is wrapped about the mandrel in such a manner that the opposite edges of the press board meet in a butt joint. The meeting edges of this joint are held in position by a strip indicated at 3, the press board base being shown at 2. The strip 3 overlies the edges and is cemented or otherwise suitably secured in 70 75 place.

A thin piece of wood veneer, with the fibers or grain thereof running lengthwise, is then cut to substantially the same shape 80 as the press board blank which forms the base and is wrapped around the exterior of the base while the latter is still mounted on the mandrel. The wood veneer is wrapped in such a manner that its meeting edges form a butt joint diametrically opposite the 85 butt joint of the base. With reference to Figs. 2 and 4 it will be seen that the wood veneer is indicated at 4 and is wrapped around the mandrel, or rather around the base 2, in such a manner that the butt joint 90 formed at 5 is directly opposite the butt joint 6 of the base. Before applying the wood veneer the exterior surface of the press board base is suitably prepared to receive the same, that is by the addition of a 95 coating of cement, glue or other substance so that the wood veneer adheres in position.

The body of the mute, after being built up in this manner, is ready to receive the diaphragm 7 which forms the closure for 100 the larger end of the body. This diaphragm is sufficiently heavy, with respect to the remainder of the body, to be substantially non-vibrating under the influence of tones issuing from the instruments with which the 105 mute is used. The diaphragm 7 is built up

of three plies 8, 9 and 10 of wood suitably cemented together and with the grain of each ply being at right angles to the grain of adjacent plies.

5 The diaphragm is inserted endwise into the larger end of the body and cemented in place securely.

On the exterior of the mute body are cemented gripping members 11, 12 and 13 10 which serve to space the mute from the bell of the cornet or other instrument with which it is used so that the tones may by-pass the mute at the side, thus extracting the strident or jazz center tones which issue from the 15 instrument.

To protect the smaller end of the mute from injury a metallic ferrule 14 is crimped or otherwise secured over the edge of the mute body at the small end.

20 It is obvious that with this construction I have provided a mute which is not subject to any of the defects inherent in metallic, papier-mâché or gutta-percha mutes and consequently provide a device which 25 will stand up under continued use. Furthermore, the resonant qualities of the wood serve to impart a very mellow tone to the instrument with which the mute is used and which is enhanced by the substantially non- 30 vibrating qualities of the end diaphragm 7 of the mute.

While, in the foregoing, I have described a specific embodiment of my invention, it is nevertheless to be understood that in carrying the same into practice I may resort 35

to any and all modifications falling within the scope of the appended claims defining the invention.

I claim:

1. A mute comprising a frusto-conical 40 hollow press board base; a veneering of wood applied to the exterior thereof and a diaphragm closing the larger end of the base, the various elements being permanently secured together. 45

2. A mute comprising a hollow press board base, the edges of said base being brought together in a butt joint; a wood veneering applied to the exterior of said base and having the edges thereof brought 50 together in a butt joint, said joints standing in staggered relation; means overlying and sealing the butt joint of the base; and a diaphragm closing one end of said base, the various parts being permanently secured 55 together.

3. A mute of the type described comprising a hollow conoidal shaped body having its exterior formed of wood veneer, and a diaphragm of wood, relatively heavy with 60 respect to the body portion, for closing the butt or larger end of the body and secured thereto, said diaphragm being composed of a plurality of laminations or plies of wood secured together with the grain of each ply 65 arranged substantially at right angles to the grain of the adjacent plies.

In testimony whereof I hereunto affix my signature.

JOSEPH KEMP HOFFMAN.
